PRINTING-TELEGRAPH SYSTEM AND ALPHABET.

1,145,460.

Specification of Letters Patent.

Patented July 6, 1915.

Application filed November 12, 1910. Serial No. 591,936.

To all whom it may concern:

Be it known that I, CHARLES G. ASHLEY, a citizen of the United States of America, and a resident of Chicago, county of Cook, 5 and State of Illinois, have invented a new and useful Improvement in Printing-Telegraph Systems and Alphabets, of which the following is a specification.

My invention pertains to rapid printing 10 telegraph systems and relates particularly to certain novel improvements in that class of printing telegraph systems, wherein the recorded characters are formed on a receiving surface by imprinting in proper relation 15 a plurality of elemental types representing collectively the respective component parts of any complete character.

In a system employing the principle of 20 elemental pens, the number of pens employed is limited by the selective facilities available and operating over the transmission line, and the resulting complete characters sometimes take forms in some cases misleading and confusing except to the initiated.

In my present invention I employ a novel 25 transmitter, receiver and circuit arrangement, which enables me to transmit, in a predetermined sequence, current impulses of variant intensities and variant polarities, to cause the selective operation of type faces to record on a receiving surface characters of the Roman alphabet that are directly readable by the uninitiated layman, placing 30 no requirement upon the receiving operator, but that he shall be able to read a language printed in Roman characters.

In the figures which accompany and form 35 a part of this specification and in which like numerals denote corresponding parts throughout, Figure 1 illustrates in diagram the circuit arrangements at both a transmitting and receiving station, together with the line conductors connecting them; Fig. 2 illustrates a section of transmitting tape as used with my improved system; Fig. 3 illustrates the monogram which is an arrangement of the type elements or printing faces as they would appear were 50 all of the types imprinted simultaneously on

the receiving surface; Fig. 4 illustrates a transmitting tape in sections, showing the arrangement of perforations for sending all of the letters of the alphabet and the numerals from 1 to 0. Fig. 5 is a diagrammatic 55 perspective view of the transmitting apparatus and circuits of my device; Fig. 6 is a plan view of the under portion of my receiver; Fig. 7 is an elevation partially in section of one of the receiving magnets and 60 printing pens of my device, showing the recording tape and its relation to the printing pens.

Referring to Fig. 1, conductors 40 and 41 are the transmission line conductors, at the 65 left are the transmitting devices, and at the right are the receiving devices, shown in symbol in order to make clear the electrical circuits. Electrically considered, the object of the system of Fig. 1, is to control selectively the operation of the printing pens 20', 20², 20³, 20⁴, 20⁵, 20⁶, & 20⁷, of the receiving device 20, by means of circuits closed selectively through the tape perforations between the brushes 6, 7 and 8, and 9 and 10, 75 the controlling circuits being formed over the conductors 40 & 41 and ground, the actuating electromotive force being supplied by the generators 2 and 3, and the polarity of the actuating currents being controlled by 80 the commutating device 17, while the intensity of the actuating currents is determined by the transverse spacing of tape perforations, which allow of shunting the actuating currents through low resistances 13, 14, 85 11 and 12, respectively.

Describing first the receiving devices in order that the requirements of the transmitting devices may be more easily understood, 90 reference is made to Figs. 1, 3, 6 and 7. The printing types 20', 20², 20³, 20⁴, 20⁵, 20⁶, and 20⁷, are carried on the outer extremities of armatures 30' to 30⁷ inclusive whose other extremities are pivoted in the members 40' 95 to 40⁷, inclusive, which in turn are rigidly supported by the polarizing magnets 50' to 50⁷ inclusive, which are mounted radially on a brass disk 55. The printing types 20', etc. are normally held against the tension of 100

springs 31', etc. out of contact with the recording tape 56 through the influence of the polarizing magnets 50' etc. Thumb screws 32' etc. carried by the members 40', etc., pass 5 through an elongated aperture in the armatures 30', etc. and serve as a means for adjusting the tension of the springs 31', etc. Seven electro-magnets, 60', 60², 60³, 60⁴, 60⁵, 60⁶, and 60⁷, are mounted on the permanent 10 magnets 50', etc., respectively, and are associated each with one of the printing pen armatures 30', etc., respectively. The windings of the magnets controlling the pens 20' and 20², are shown placed in series with each 15 other and connected to the line conductor 41 and ground, while the windings of the magnets controlling pens 20³ and 20⁴ are placed in series with each other and connected to the other line conductor 40 and ground. 20 The windings of the magnets controlling auxiliary pens 20⁵, 20⁶, and 20⁷, are bridged on the windings controlling primary pens 20', 20², and 20⁴, respectively as shown in Fig. 1. The polarizing magnets 50', 50⁶, 25 and 50⁷ polarizing auxiliary pens 20⁵, 20⁶, and 20⁷, and their respective electro-magnets, may be stronger in their magnetism than the polarizing magnets polarizing primary pens 20', 20², 20³, and 20⁴, or the 30 helices of the electromagnets may have variant numbers of turns to effect an equivalent ultimate operation. The windings of each pair of the magnets 60' and 60², 60³ and 60⁴, are arranged so that a current impulse of 35 one polarity and intensity over one line conductor and the ground will release one pen of that pair of pens in the particular line by neutralizing in the core of its electromagnet that magnetism induced by its permanent 40 magnet and allow it to be propelled by its spring to make an imprint of its particular type face upon the recording tape 56, while the other pen of the pair will be held to its controlling magnet whose normal magnetism will be strengthened by the line current. 45 However simultaneously with the current through the magnets of the primary pen a current has passed also through the magnets of one or two of the auxiliary pens, and if 50 the current intensity of the impulses sent over one of the line conductors and ground should be of a value sufficient to overcome the attraction of polarizing magnets 50', 50⁶ or 50⁷, not only will one of the pens of a 55 particular pair as 20' and 20² be released to imprint its type face, but also the pen controlled by the bridged electro-magnet as 20³ or 20⁴ and polarized by the intensity of magnetism of the magnet 50⁵ or 50⁷, will be imprinted simultaneously with the pen of the 60 pair 20' and 20². Thus it will be seen that by sending a positive impulse of a current intensity within predetermined limits over line 40 through magnets controlling pens 20⁴, 20³, and 20², that pen 20⁴ may be im- 65

printed alone, that by sending a negative impulse of the same intensity over the same line pen 20³ may be imprinted alone and that by sending a negative impulse of relatively greater current intensity over the same line 70 pens 20³ and 20⁴ may be imprinted simultaneously. In like manner, by sending impulses of predetermined polarity and intensity over line 41, pens 20' or 20² may be selectively imprinted and pens 20' and 20⁵ 75 or 20² and 20⁷ may be simultaneously imprinted, as indicated above, while in each case the pen or pens in a particular line not imprinted by impulses over the line, will be more strongly attracted by their controlling 80 magnets, while the actuated pen or pens are being imprinted. In the circuit diagram Fig. 1, it may appear that the equilibrium of current values may be disturbed by the fact that the coil 20¹ has no companion or auxiliary coil. The conductors 40 and 41 are line conductors and by reason of length they will in practice have high resistances, hundreds of ohms, whereas the magnets 20' to 20⁷ are comparatively very low, preferably less than 90 ten ohms, so that the currents over 40 are substantially the same as over 41 for the same applied potential. Magnets 20³ and 20⁴ then get the same current values and current conditions as magnets 20' and 20². The 95 magnet 20⁴ is not subject to quantitative discrimination. The circuit connections of the three magnets, 20³, 20⁴, and 20⁶, *inter se* is immaterial whether series, multiple, etc., so long as all participate in currents received 100 over the line conductor 40, the turns of each and the permanent field strength of each being so adjusted that a greater current intensity is required to operate the pen magnet 20⁶ than is required to operate the pen of 105 magnet 20³. The same is true of pens 20', 20², 20⁵ and 20⁷ and the line conductor 41, the final and critical adjustments being that pens 20⁵ and 20⁷ require greater operating 110 currents than pens 20' and 20².

An anvil 57 is placed opposite the printing face of the pens. The recording tape 56 lies upon the surface of the anvil and is drawn laterally from the roll of tape 58, before the printing faces of the pens by means 115 of rollers 59. The receiver illustrated is arranged for electro-chemical printing and a battery 54 is connected to the pens and the anvil for that purpose.

The transmitting device, together with 120 its associated circuits, is shown in Fig. 5 and comprises a drum 71 of metal or insulating material, carrying centrally on its circumference a row of pins 71' and driven by belt from any source of power. A drum 70 bears 125 upon drum 71 and is driven thereby. A central row of apertures 70' in drum 70 permit of the invagination of the pins 71'. An impulse alternator 17 comprising a series of insulated contacts 15', 15², 15³, 15⁴, and 4 is 130

mounted rigidly upon the frame of the transmitter and provided with a contact maker 16 rotated simultaneously with the drum 71 and at a fixed relative rate of rotation by 5 means of spur gears 72 and 16', thus always maintaining a definite relation between the position of the contact maker 16 with respect to the contacts 15', 15², 15³, 15⁴, and 4 and the drum 71 for any instantaneous position 10 of the drum 71. Brushes 6, 7 & 8 are rigidly mounted upon the frame of the transmitter and are insulated therefrom and from each other. As will be explained subsequently a definite distance is at all times 15 maintained between the brushes and the rollers 70 & 71. A pair of flexible brushes 9, 10 are mounted in a brush holder carried by the frame of the transmitter and are adapted to make contact with and between 20 the brush 6 and brushes 7 and 8 respectively. The contracts 15' and 15³ of the alternator 17 are connected to the negative terminal of the generator 2 while contacts 15² and 15⁴ are connected to the positive terminal of similar 25 generator 3. The generators have their remaining terminals connected together and grounded at 1. Contact 4 of impulse alternator 17 is connected to brush 6. Brush 9 is connected through a relatively high resistance 30 11 with line conductor 40, while brush 10 is connected through a relatively high resistance 12 whose value is the same as resistance 11, with line conductor 41. Brush 7 is connected through a conductor 13 of sub- 35 stantially zero resistance with conductor 40, and brush 8 is connected through conductor 14 of equal resistance with conductor 13, to line conductor 41.

The wiper of alternator 17 is adapted to 40 make contact between the insulated contacts 15' and 4, 15² and 4, 15³ and 4, etc., thus placing potential impulses of predetermined polarity upon brush 6. A tape 44 is adapted to be passed from a roll of such tape 44², 45 between the brushes 9 and 10 and the brushes 6, 7 and 8 and between the rollers 70 and 71. The friction of the tape and rollers is adapted to cause the longitudinal movement of the tape between the brushes, and a series 50 of central perforations 44' in the tape are adapted to register with and be engaged by the pins in the drum 71, thus serving at all times to maintain a predetermined register 55 between the tape and the surface of the drum 71, during the longitudinal movement of the tape through the transmitter. The transmitting tape, through perforations 60 therein, permits contact of brush 9 with brush 6 or with both brushes 6 and 7; similarly brush 10 may make contact with brush 6 or with both brushes 6 and 8; thus either line conductor may be connected through resistance with the impulse alternator 17 and through the impulse alternator with 65 grounded generators 2 or 3, or either line

conductor may be connected through substantially zero resistance with the impulse alternator and through the impulse alternator with grounded generators 2 or 3. These contacts through the transmitting 70 tape are selective in two functions.—First, in selecting the proper contact between the brushes and, second, in selecting the proper instant with reference to contacts made previously or to be made subsequently. A time 75 relation exists between the speed of the transmitting tape and the speed of the wiper 16 of impulse alternator 17, which permits of the selection of the proper polarity of the impulse. A time relation also exists between 80 the speed of the transmitting tape, impulse alternator and recording tape, that the printed components of the characters may be properly spaced and further that the characters may be correctly spaced from 85 each other on the recording tape.

The recording tape as well as the transmitting tape is moved longitudinally in any well known manner. I prefer, however, to employ a small electric motor driving rollers, as indicated at 59 and at 70—71 in the figures which serve to pull the tape at a uniform and proper speed through the respective devices.

Control of the printing pens 20' to 20⁷ by 95 perforations in the tape 44 is as follows: The perforations in the tape 44, Fig. 2, are confined to four longitudinal rows 6'; 3', 4'; 1', 2' and 7', 5' of Fig. 2. The row of central perforations 44' in the tape are, as has 100 been said, spaced to admit the pins on the drum 71, the spacing of the pins being in such relation with the speed of the drum 71 and wiper 16 of alternator 17 as to allow of 105 wiper 16 making contact successively between any two contacts as 15' and 4 and passing to the middle portion of a third contact while the drum 71 is rotated a distance equal to that defined by that portion of its circumference included between any two 110 pins 71'. Further the number of the pins on the drum is such and their relation to the wiper is so coördinated that when any pin is in a vertical position the wiper is making contact between contact 4 and a contact 115 connected to the positive terminal of the generator. The brushes 6, 7 and 8 are disposed a distance away from the axis of rotation of the drum 71 such that when the tape is placed in position to transmit a message 120 the contact line between the brushes when any pin or drum 71 is in a vertical position will fall on one of the central perforations in the tape. Thus by properly spacing longitudinally and transversely the perforations between any two central perforations of the tape 44, positive and negative impulses of variant intensities may be selectively sent over either line through its associated receiving magnets, and the ground 51 125 130

or impulses of like polarity and variant intensities may be sent simultaneously over both lines.

- By noting the position of the drum 71 to ascertain that one of its pins is in a vertical position and remembering that the wiper moves two contacts while the tape moves one tape interval, a perforated tape may be placed in position and passed longitudinally from right to left under the brushes 9 and 10 as viewed in the figure and circuits may be traced to transmit through any perforation in the line (1', 2') of the tape and opposite any central perforation a positive current impulse through resistance 12 and line conductor 41 through the receiving magnets associated with that line and ground, to operate pen 20² to cause it to imprint its type face, while any perforation spaces in the tape along the same line but half way between any two central perforations or at the second tape interval will cause a negative impulse to be sent through the same circuit to cause the operation of pen 20¹. Similarly perforations in the tape along the line (3', 4') will allow of a positive or negative impulse being sent through resistance 41 and line conductor 40 to operate selectively pens 20³ and 20⁴. It will be noted that two perforations may be placed in the tape opposite each other, one in line (3', 4') and the other in line (1', 2') and when so placed will allow a positive or negative impulse being sent over both lines simultaneously to operate simultaneously pens 20¹, 20², or 20³, 20⁴, dependent upon the longitudinal position of the perforations in the tape.
- Any perforation placed on the line (7', 5') in the tape and opposite a perforation in line (1', 2') will permit an impulse of relatively greater intensity, and of the same polarity as that indicated by the position of the perforation on the line (1', 2') being sent over the line 41 to cause the simultaneous operation of pens 20², 20⁷, or 20¹, 20⁵, as the case may be, for when two perforations are disposed as just described a circuit is closed from ground generator 3 and through impulse selector 17 to brush 6 thence through perforation in tape on line (1', 2') to brush 10 thence through brush 10 and through the second perforation in the tape to brush 8 and through conductor 11, shunting resistance 12, to line conductor 41 and through the receiving magnets of that line to ground, thus greatly reducing the resistance of the path of the impulse as compared with the path through resistance 12 and line 41 which may be considered the normal path, and hence allowing a greater current value to flow for a given electro motive force, and causing, as has been before described, the operation of both the pen responsive to low or normal currents and the pen responsive only to stronger currents. Simi-

larly, a perforation placed in the tape along the line 6' and opposite a perforation in the line 3', 4' of Fig. 2 placed in the second tape interval, or between central perforations 44', will permit a negative impulse being sent through conductor 13 to line 14 to operate simultaneously pens 20³ and 20⁴.

Fig. 3 shows the arrangement of the printing faces of the pens 20¹ and 20², the imprints being shown as if printed on a stationary receiving surface or as though all seven pens were printed simultaneously upon a moving surface. Three tape intervals, or time intervals, are considered equal to the entire width of the combined symbol as indicated by the dotted lines, and the horizontal elements are each considered to be two tape intervals in length. Pen 20¹ is controlled through perforations in the tape 44, Fig. 2, spaced on line 1', 2' of Fig. 2 and midway between any two central perforations or in the second tape interval, and the others are controlled by perforations spaced at stated tape intervals along the lines 6'; 3', 4' and 7', 5' of Fig. 2 as has been described. The method of combining these individual imprints of the pens to produce an intelligible character is as follows; referring to Figs. 1, 2 and 3, considering the recording tape to pass from right to left under the symbol of Fig. 3, while the transmitting tape as viewed in Fig. 2 is passing from right to left under the brushes 9 and 10 of Fig. 5. The letter A is produced by first imprinting pen 20⁴ and after a lapse of two time intervals imprinting simultaneously pens 20² and 20¹ and then after a lapse of one time interval imprinting pen 20⁷. The letter S is produced by first imprinting pen 20² and after a lapse of one time interval imprinting simultaneously pens 20⁴, 20⁵ and 20³, 20⁶. The letter H is printed by imprinting first pen 20⁴ and after a lapse of two time intervals printing simultaneously pens 20² and 20¹. Referring to Fig. 4, in which I have shown the proper tape perforations for sending an alphabet and figures, the letter P is imprinted by first imprinting pen 20⁴ and after a lapse of two time intervals simultaneously imprinting pens 20² and 20⁷ and then after the lapse of one time interval imprinting pen 20¹.

It will be observed from the foregoing that in order to produce a letter or a numeral on a receiving surface it is only necessary to print the proper predetermined pens with a proper predetermined number of time or tape intervals between the intervals of printing, the number of time units being dependent upon the result desired.

The speed of the transmitting tape, impulse selector, and recording tape is such as to move the transmitting tape one tape interval in the time required to produce the

corresponding distance unit upon the recording tape. This requirement merely places a required ratio upon the speed of the transmitter and receiver and this ratio 5 may be adjusted after an inspection of the work done. It will be observed that as a constant angular relation is maintained through the gearing 72 and 16' between the wiper 16 and the drum 71 and as the regulation 10 is such as to allow of two complete impulses being placed on the brush 6 during the angular rotation of the drum 71 through a distance represented by that between any two pins on the circumference of the drum, 15 it is only necessary in a perforated message tape to provide that a predetermined tape interval, whether perforated to send an impulse or not shall fall opposite one of the central perforations in the tape. When a 20 tape is so perforated with a message, it may be placed on the drum so that its central perforations register with the pins on the drum, and if the perforations have been properly spaced both longitudinally and 25 transversely the message will be automatically recorded at the receiver.

It will be observed that each elemental line when imprinted merely abuts a previous print and that the completed character 30 is formed without allowing any portion of one imprint to overlap or register with another. Then too every letter or numeral is printed without any useless appendage, thus greatly increasing the clearness of the recorded message. This gain when taken in 35 connection with a transmitting tape of only four rows of perforations results in producing a device of great commercial utility.

Further it will be noted that as I am enabled 40 in my device to simultaneously imprint two pens or more with but a single impulse of one polarity, that the number of impulses for a given message will be small as compared with the number of pen operations required resulting in a slower commutation 45 of currents in the line for a given speed of transmission as measured in number of words per unit of time.

While I have illustrated my device in connection 50 with two direct current generators as a source of supply, it is obvious that I may utilize any other well known source of supply. Further it is obvious that while I have shown a particular design of transmitting and receiving devices, many modifications 55 may be made therein without departing from the spirit or narrowing the scope of my invention.

Having thus described my invention, what 60 I claim as new and desire to secure by United States Letters Patent is:—

1. In a system of printing telegraphy, a transmitter; a receiver, and conductors connecting same; said transmitter comprising 65 a plurality of insulated conducting mem-

bers; means for impressing on one of said conducting members, in predetermined sequence and at predetermined time intervals, current impulses of predetermined polarity; and means for selectively transferring to 70 said conductors, from said conducting member, current impulses of predetermined polarity and intensity to cause the operation of said receiver.

2. In a system of printing telegraphy, a 75 transmitter; a receiver, comprising seven printing pens; and a pair of line wires and ground connecting same; said transmitter comprising a plurality of insulated conducting members; a plurality of collecting members bearing on said conducting members; a source of current, and means whereby impulses of variant polarity and intensity from said source may be permitted through said collecting members to said lines and ground 80 to operate selectively said printing pens.

3. In a system of printing telegraphy, a transmitter; a receiver; and conductors connecting the same; said receiver comprising a plurality of printing pens; a conducting 90 member in said transmitter; means for impressing upon said conducting member of said transmitter, in predetermined sequence and at predetermined time intervals, current impulses of predetermined polarity and 95 duration and constituting in substance an alternating potential impressed upon the said member; collecting members associated with said conducting member and adapted to transfer impulses of selective polarity and 100 intensity to said line conductors to cause the selective operation of said printing pens at said receiving station.

4. In a printing telegraph system, a transmitting station; a receiving station; and line 105 conductors and ground connecting them; a source of current at the transmitting station; a transmitter adapted to send to said line and ground, in predetermined sequence, current impulses from said source of predetermined polarity and intensity, in accordance 110 with a predetermined code; a recording surface at said receiving station; a set of seven printing pens adapted to print thereon; and a set of magnets controlling said pens and 115 actuated selectively by said current impulses to cause said pens to imprint on said receiving surface the characters of the Roman alphabet.

5. In a printing telegraph system, a transmitter; a receiver, and line conductors and ground connecting same; said receiver comprising seven printing pens adapted to each imprint a single elemental line, said pens being controlled by magnets; a pair of said 125 magnets being connected in series with each other in each of said line conductors and controlling a pair of pens, and the remaining three of said magnets being bridged on three of the first mentioned magnets and 130

thereby constituting themselves auxiliary magnets; means at said transmitting station whereby current impulses of a definite polarity may be transmitted over said lines and ground to operate certain ones of said pairs of pens; and means whereby impulses of the same polarity, but of increased current intensity, may be transmitted over said lines and ground to operate simultaneously certain ones of said pairs of magnets and their companion bridged auxiliary magnets

to selectively cause the pens of both magnets to imprint their said elemental lines to abut to form legible characters.

Signed by me at Toronto, county of York, 15 and Province of Ontario, in the presence of two witnesses.

CHARLES G. ASHLEY.
